(57) **CLAIM**

The ornamental design for a light for outdoor light string as shown and described.

DESCRIPTION

FIG. 1 is a perspective view of a light for outdoor light string showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the light for outdoor light string in a configuration of use.

The broken lines in the drawings depict portions of the light for outdoor light string that form no part of the claimed design. The additional broken lines in FIG. 9 represent environment and form no part of the claim.

1 Claim, 9 Drawing Sheets
